HAT CARTON

Everett C. Johnson, Berwyn, Ill., assignor to
Montgomery Ward & Co., Incorporated, Chi-
cago, Ill., a corporation of Illinois

Substituted for application Serial No. 502,584,
September 16, 1943. This application February
12, 1945, Serial No. 577,354

2 Claims. (Cl. 206—8)

1

This invention relates to cartons, and more particularly to cartons especially adapted for the shipment of light weight merchandise requiring positioning within the carton such as hats and the like.

Heretofore in cartons adapted to safely pack-
age hats, a filler structure adapted to maintain
the hat in one position was required, which
structure was of a complicated costly nature, and
entirely separate from the carton.

It is an object of the present invention to pro-
vide a carton for the shipment of hats and the
like, wherein the hat is maintained in a proper
position within the carton by simplified means,
at least a portion of which is formed from the
carton structure itself.

A further object of the invention is to provide
a carton in which one pair of the usual overlap-
ping flaps is cut to form a centering boss or hub
within the carton on the top or bottom side of
the carton.

A further object of the invention is to provide
in a carton bent up portions of a pair of the
carton closure flaps to form, in cooperation with
a tubular transverse member to be placed in the
carton, a rigid centering and holding construc-
tion for centering a hat shaped item within the
carton.

The above and other novel features of the in-
vention will appear more fully from the follow-
ing detailed description, when taken in conjunc-
tion with the accompanying drawing. It is ex-
pressly understood, however, that the drawing
is employed for purposes of illustration only and
are not designed as a definition of the limits of
the invention, reference being had for this pur-
pose to the appended claims.

Referring to the drawing in which like refer-
ence characters indicate like parts:

Figure 1 is a perspective view of a carton em-
bodying the invention, the top flaps being open
and a portion thereof being broken away to show
the inside detail.

Figure 2 is a section taken on the plane 2—2 of
Figure 1, as viewed upwardly, the outer top flaps,
however, being shown closed.

Referring to the drawing, a substantially
standard rectangular corrugated cardboard car-
ton, modified in accordance with the invention,
is illustrated. The carton comprises sides 10
and 12, and ends 14 and 16, together with their
 appended top and bottom flaps, it being appre-
ciated that such cartons with the appended flaps
of the respective sides folded parallel therewith
are shipped in large quantities folded flat. By

2

folded flat is meant the diagonally opposite cor-
ners, for example, 18 and 20 are flattened while
the corners 22 and 24 are bent to a full 180 de-
grees.

5 The ends 14 and 16 are provided with their
usual bottom flaps 26 and 28, which together with
the bottom flaps 30 and 32 of the sides 10 and 12
cooperate to close the bottom of the carton when
set up as shown in Figure 2.

10 In order to provide a centering "boss" or in-
wardly projecting shoulder adapted as in the illus-
tration to fit within the crown of a hat 34, the
ends of the top flaps 36 and 38 appended to the
sides of the top flaps 36 and 38 appended to the
15 sides 16 and 18 are cut inwardly from their side
edges, along the lines 35 and 37, toward the center,
but short of the center and parallel to the end
edge 39 of the flap. There is thus provided a cen-
ter section 40, adapted to be bent inwardly as
20 shown on the line 41, and centrally bent tongue
portion 42 and 44 adapted to cooperate with the
center section, and a similar set of tongues upon
the opposite flaps 38 to form a substantially six-
sided hollow stub centering post, adapted to be
25 resiliently sprung within the crown of the hat 34.

To hold the hat upwardly against the top cover
and in position over the centering post or boss
formed from the portions 40 and tongues 42 and
30 44, a tubular member 48 is provided, which may be
of cardboard or the like, and which is of sufficient
length to fit against the outside upper surface
of the brim of the hat or other item to be held,
closely adjacent to the crown thereof, and to
35 support the brim of the hat against the top flaps
36 and 38 from the bottom flaps 26 and 28.

40 To pack a hat in such a carton, the bottom
flaps are closed and sealed in any suitable man-
ner. The tubular member 48 is assembled
around the hat, the hat and tube inverted and
45 inserted into the carton. The central portion 40
and tongues 42 and 44 of each flap 36 and 38 are
next bent into the crown of the hat, and the top
side flaps 50 and 52 folded down and seated.
Thus through the simple addition of a light
tubular element, and a common strawboard car-
ton, a rugged safe carton for shipment of light
objects, such as hats, is provided.

50 Though the invention has been illustrated and
described in a single embodiment of rectangular
shape and is adapted for special application to
hats or the like, it will be appreciated that the
invention is not limited thereto, but may be em-
bodied in various modifications and arrange-
ments which may be made without departing
from the spirit of the invention as will be ap-

parent to those skilled in the art. Accordingly, reference will be had to the appended claims for a definition of the limits of the invention.

This application is a substitute for my application Ser. No. 502,584, filed Sept. 16, 1943.

What is claimed is:

1. A carton for a hat or the like, comprising a bottom, side walls, and transversely arranged pairs of non-overlapping closing flaps, each pair being adapted to close the carton to a substantial degree, and one pair being within the other pair when in closed position, and means on said one pair of flaps formed wholly from the flaps and extending within the carton and projecting into the crown of a hat, said means comprising an inwardly folded portion of each flap folded on a line parallel to the flap fold with the said portion severed from opposite sides along the portion fold to provide tongues, said tongues being bent toward the opposite flap on a fold extending perpendicular to the plane of the closing flaps, and means extending from the bottom for maintaining a hat with its crown centered around said projecting means.

2. A rectangular carton comprising a bottom, 25

side walls, and a top including pair of substantially symmetrical non-overlapping folding closure flaps hingedly secured to opposite walls, each of said flaps having transverse side edges and an edge substantially parallel with the hinged edge, each of said flaps having a marginal portion parallel to said last named edge, adapted for centering an object within the carton, said marginal portion being severed from the flap from the transverse edges inwardly to a point short of the center to provide opposed tongue parts and a central portion, said tongue parts being foldable along lines parallel with the transverse edges, and said central portion being foldable along the unsevered portion of the line of severance, whereby said central portions of the marginal portions of each flap may be folded inwardly of the carton, and said tongues folded toward the center of the cover flaps, to form a six-sided inwardly extending boss, said tongues being adapted to bear along the severed edges against the top, to retain the central portion bent at substantially right angles to the remainder of its flap.

EVERETT C. JOHNSON.
